UNITED STATES PATENT OFFICE

KENNETH R. HALEY, OF BEAVER, PENNSYLVANIA, ASSIGNOR TO THE PHOENIX GLASS COMPANY, OF MONACA, PENNSYLVANIA, A CORPORATION OF WEST VIRGINIA

DESIGN FOR A BOX OR SIMILAR RECEPTACLE

Application filed November 30, 1929. Serial No. 33,591. Term of patent 3½ years.

To all whom it may concern:

Be it known that I, KENNETH R. HALEY, a citizen of the United States, residing at Beaver, in the county of Beaver, State of Pennsylvania, have invented a new, original, and ornamental Design for a Box or Similar Receptacle, of which the following is a specification, reference being had to the accompanying drawing forming a part thereof.

I claim:

The ornamental design for a box or similar receptacle, as shown.

KENNETH R. HALEY.
